DESIGN FOR A PARKING METER

David C. Rockola, Chicago, Ill.

Application April 16, 1936, Serial No. 62,154

Term of patent 14 years

To all whom it may concern:

Be it known that I, David C. Rockola, a citizen of the Dominion of Canada, residing at Chicago, in the county of Cook and State of Illinois, have invented a new, original, and ornamental Design for Parking Meters, of which the following is a specification, reference being had to the accompanying drawing forming part thereof.

Fig. 1 is a front elevational view; and
Fig. 2 is a side view of the parking meter embodying my new design.

I claim:

The ornamental design for a parking meter, as shown.

In witness whereof, I hereunto subscribe my name, this 14th day of April, 1936.

DAVID C. ROCKOLA.
